Primary Examiner — Kevin Rudzinski(74) *Attorney, Agent, or Firm* — Greenberg Traurig, LLP(57) **CLAIM**

The ornamental design for a display screen with graphical user interface, as shown and described.

DESCRIPTION

FIG. 1 is a front view of a display screen with graphical user interface showing a first embodiment of my new design; FIG. 2 is a front view of a display screen with graphical user interface showing a second embodiment of my new design; and,

FIG. 3 is a front view of a display screen with graphical user interface showing a third embodiment of my new design. The broken line drawings of the computer display screen and various regions therewithin are for illustration only and forms no part of the claimed design. The broken line words, letters, numbers, and various graphical representations are for illustrative purposes only and form no part of the claimed design.

1 Claim, 3 Drawing SheetsFIG. 1

FIG. 2

FIG. 3
